UNITED STATES PATENT OFFICE.

FRANK J. WAGNER, OF YONKERS, NEW YORK.

BAG-TURNING MACHINE.

Application filed October 15, 1920. Serial No. 417,276.

To all whom it may concern:

Be it known that I, FRANK J. WAGNER, a citizen of the United States, residing at Yonkers, in the county of Westchester, 5 State of New York, have invented certain new and useful Improvements in Bag-Turning Machines, of which the following, taken in connection with the accompanying drawings, is a specification.

10 My invention relates to machines for turning or reversing bags and sacks, and its object is the construction of a machine for this purpose that will turn or reverse bags and sacks, more particularly of the larger 15 sizes, efficiently and rapidly.

It is to be understood that the construction shown and described is an illustrative embodiment merely, and that variations and modifications may be made that will, nevertheless, 20 be within the scope of my invention as defined by the claims hereto appended.

Referring to the drawings, Figure 1 is a plan view of my machine, and Figure 2 is a side elevation thereof, the supporting 25 parts, however, not being shown. Figure 3 is an enlarged detail of the mechanism for holding and opening the bag, whereby it may slip easily on to the bag frame. Figure 4 is a transverse section on the line 4—4 30 of Figure 1, the bag frame being omitted for the sake of clearness. Figure 5 is an enlarged detail view showing the mechanism whereby a bag carried by the belt conveyor may pass the bag frame. Figure 6 is a side elevation showing in enlarged detail the plunger and mechanism for operating the plunger. Figure 7 is a plan view 35 enlarged showing in detail the plunger carrying a bag and the mechanism for operating the plunger in position preparatory to the turning movement. Figure 8 is a plan view enlarged showing in detail the bag-turning mechanism at the completion of the 40 operation of turning a bag.

45 Support for the operating parts is supplied by a main frame 1, which in turn may be supported by suitable standards 2. Power may be imparted to the machine through any convenient means such as the pulley 3 mounted on the shaft 4, which also carries the loose pulley 5 to which the belt 50 may be shifted in the usual manner for stopping the machine. A belt conveyor for

causing the necessary travel of bags to be turned may consist of the endless belt 6 55 travelling continuously in the direction of the arrow A on the pulleys 7 and 8, the former being mounted on the shaft 9 and the latter on the driven shaft 10. The shaft 9 may, if desired, be mounted in bearing 60 blocks 11, mounted to slide in the guides 12 and may be set in any desired position in the guides by turning the bolts 13 threaded in the frame 13^a, and bearing against the blocks 11 against the tension of the conveyor belt. Adjustment to take care of excessive slackness or tautness of the conveyor belt is thus made possible.

65 My construction as shown in the drawings involves the employment of a bag frame 14 over which is turned the bag and a plunger 15 having relative movement with respect to the bag frame. The plunger is preferably framework structure as shown in Figures 1, 2 and 3. The bag frame may 70 take the form of a member having approximately the shape of the block letter U, and preferably is stationary with respect to the motion of the conveyor having, however a pivotal connection whereby it may be swung 75 or tilted upwardly from the path of a bag travelling on the conveyor, as will be hereinafter further explained.

80 Any suitable mechanism may be supplied for actuating the plunger; for instance, it may be given a motion the reverse of the travel of the conveyor belt which is indicated by the arrow (Figure 1). To secure 85 this reverse action, it may be mounted on shafts 16 and 17, which, in turn, are mounted on flanged wheels 18. The flange wheels operate between rails 19, so that the plunger at all times remains in substantial parallelism with the travel of the conveyor. The travel of the plunger may be controlled in 90 any convenient manner such as by fixedly connecting the ends of the shaft 16 and 17 through the medium of members 20, with the outer stretches of endless belts 21 carried by the loose pulleys 22. The inner 100 stretches of the belts 21 are supplied with studs 23 and when projections 23^a on the moving conveyor engage the studs 23, as will be hereinafter explained, a reverse motion, that is, a motion of the plunger in the 105 direction of the bag frame is brought about.

The return motion of the plunger may be brought about in any convenient manner such as by means of the studs 24, projecting from the conveyor belt which, as they travel along, butt against the shaft 17, the resulting engagement being released as the studs 24 pass over the pulley 8.

In order that a bag carried by the conveyor may slip easily over the plunger, it is desirable that some form of bag holder be provided for holding the mouth of the bag distended. Preferably the bag holder is such that the bag does not become distended until after it is evenly inserted thereon. Such a bag holder is shown in Fig. 1 and a detail thereof in Fig. 3. It may consist of two wings 25, mounted on a plate 26, mounted on and extending transversely of the conveyor. The wings are pivoted by means of spring hinges 27, which normally hold the wings in a perpendicular position, namely, the position indicated by the dotted lines in Fig. 3.

To facilitate the insertion of a bag on the holder, it is desirable that at the time of insertion the wings be in a horizontal position, which object may be secured by providing spring catches 28 which are strong enough to hold the wings horizontally, as against the tension of the spring hinges 27. At a convenient point on the frame of the machine in advance of the mouth of the plunger, means are provided such as the cams 29 for releasing the wings from the spring catches, whereupon they assume a perpendicular position and the mouth of the bag is distended sufficiently to permit the plunger 15 to enter the mouth of the bag, whereby with continued motion of the carrier it will slip easily over the plunger.

As, in the particular construction shown, the plane of motion of the bag holder is in substantially the same plane as that of the bag frame 14, it is necessary that the bag frame be removed out of the path of a travelling bag as the latter advances or moves in the direction of the plunger.

This object may be effected by rigidly attaching the bag frame to depending members 30, 30 which in turn are pivoted at 31 to standards 32, 32 erected on the machine frame. When the frame is tilted upwardly there is sufficient space for the bag to clear as it passes beneath.

Means for tilting the frame to upward position (as shown in Figure 5) may consist of weights 33 carried by arms 34 rigidly connected with the depending members 30. The result thus far is normally to keep the bag frame in elevated position. As, however, the bag frame need be in elevated position only during the passage of a bag, and as it must be in lowered position during the action of the plunger as hereinbefore described, I provide a tripping mechanism of

such character that except during the passage of a bag frame it is maintained in lowered position as shown in Figure 2. The tripping mechanism may consist of the trip 35 pivoted to the frame 36, and having tension spring connection at the point 37 with the frame as shown. Also mounted on the frame is a bell crank lever having the longer arm 38 provided with a bevelled engaging end as shown and the shorter arm 39, and being pivoted at 40. A link 41 connects one of the arms 34 with the longer arm 38 of the bell crank lever.

To operate the trip and raise the bag frame, I provide the plate 26 with a depending ear 42, adjusted to strike the trip 35 when the latter is set and release the bell crank lever, whereby the bag frame is tilted by the action of the weights 33. When the bag holder has passed beneath the pivotal mounting of the bag frame, the latter may be again lowered, which may be effected by providing the conveyor with stud 43 affixed thereto in any convenient manner, such as being made integral with the cross bar 44 carried by the conveyor. As the stud 43 strikes the short arm 39 of the bell crank lever, the bag frame is again lowered and the trip set for the next following bag holder of which there may be a number.

As the bag holder is relieved of its bag by the action of the plunger, as hereinafter described, the wings remain upwardly extended and must be closed down before the bag holder again comes into operation. To accomplish this suitable cams 45 may be interposed in the path of the lugs 46 of the extended wings, those cams being mounted at any suitable location in advance of the position at which a bag is to be engaged, such for example as on the inclined platform 47 which is supported by standards 48. These cams are shaped to engage the lugs 46 and thus to depress the extended wings until they are engaged by the spring catches, whereby they are held until they are again caused to be extended by abutting against the cams 29.

The belts 21 may be tautened or slackened as desired by an adjustment consisting of the blocks 48, 48, in which the pulleys are mounted, which are movable and adjustable to predetermined position by the bolts 49, 49 connecting the blocks 48, with lugs 51, 51 affixed to the frame.

To maintain dependable engagement between the studs 23 and 23^a, it is advisable to provide the guides 52 affixed to the machine frame. The belts 21 may carry hooks 53 which engage with the guides 52 to prevent lateral movement of the belts and with hooks 54 which engage the under side of the guide 52 and thus prevent upward movement of the belts 21.

An inclined table 47 may be erected on the

frame of the machine to serve as a convenient place upon which to lay a pile of unturned bags and from which bags may be taken as desired to be subjected to the operation of the machine.

The operation of my machine is as follows:

Assume that the parts are in the position shown in Figure 1. The bag 55 is placed on the conveyer with its mouth enclosing the wings as shown in Figure 1. As the conveyer travels in the direction of the arrow, the lug 42 strikes the trip causing the weight 33, to fall and thus tilting the bag frame to the approximate position shown in Figure 5, whereby sufficient clearance is effected to permit the passage of the bag beneath the bag frame. As the conveyer continues the projecting lugs 46 on the wings strike the cams 29, causing the wings to be released from the spring catches whereupon they rotate by the action of the spring hinges on which they are pivoted to the position shown in Figure 6, thus holding the mouth of the bag distended. As the bag continues it is carried on to the plunger, the plunger being stationary at the commencement of this motion. When, however, the bag has been carried nearly the full length of the plunger, the lugs 23 engage with the lugs 23^a and at approximately the same time the lug 43 sets the trip by raising the weights 33 and permitting the bag frame to fall to its normal position. As the lugs 23 engage with the lugs 23^a a forward motion of the plunger in the direction of the arrow B is brought about and the bag is turned on the bag frame 14 as shown in Figure 8. Immediately the plunger has reached the limit of its forward motion, the lugs 23^a are disengaged from the lugs 23 as the former pass down over the pulley. Thereupon the lugs 24 engage with the shaft 17 on which the plunger is mounted, and the plunger is carried back to its normal position (that is, the position shown in Figures 1 and 2) carrying with it the bag. The dimensions of the plunger are such that it grasps the bag somewhat closely, and the latter is therefore prevented from dragging on the bag frame 14 to a sufficient extent to prevent it from traveling with the plunger as the plunger returns. As the bag is stripped off the bag frame 14, it falls on the conveyer and is carried off and deposited at the end of the conveyer. Thus far the wings remain in elevated position, but they are depressed before they again come into operation by striking the cams 45 whereby they become engaged with the spring catches, thus being in position to receive another bag and go through the same cycle of operation. As shown in Figure 2, for example, additional bagholders 56 may be employed, the number depending upon the length of the conveyer. Of course, with each

bag holder it is necessary to employ lugs and parts to perform the operations above described.

I claim:

1. In a bag turning machine a belt conveyer, an endless belt mounted to travel in parallelism with said conveyer, a bag holder carried by said conveyer, said bag holder comprising wings adapted to be depressed and elevated, a bag frame pivotally mounted over said conveyer to swing transversely thereof, and extending in the direction of travel thereof, a plunger slidably mounted over said conveyer and extending in a direction opposite to that of said bag frame and proportioned to encompass the same, counter weights on said bag frame adapted normally to keep the same in elevated position, a trip for maintaining said bag frame in lowered position in opposition to said counter weights, a lug on said conveyer adapted to release said trip, cams on the machine frame adapted to elevate said wings, a lug on said conveyer adapted to set said trip, lugs on said endless belt, lugs on said conveyer adapted to engage the same, lugs on said conveyer adapted to engage said plunger, cams on the machine frame adapted to depress said wings, spring catches operating with said wings to hold them in depressed position, and spring connections between said wings and said conveyer adapted to hold said wings in elevated position when the same have been released from said spring catches.

2. In a bag turning machine, a conveyer, an endless belt mounted to travel in parallelism with said conveyer, a bag holder carried by said conveyer, a bag frame, a plunger slidably mounted over said conveyer and having connection with the outer stretch of said endless belt, lugs on the inner stretch of said endless belt and lugs on said conveyer positioned to engage the last mentioned lugs whereby the said plunger is caused to travel in a direction opposite to the direction of travel of said conveyer.

3. In a bag turning machine, a belt conveyer, a bag holder carried by said conveyer, a bag frame projecting from a depending pivotally mounted bracket, a plunger mounted to slide in the plane of the bag frame and in the plane of movement of the bag holder, said plunger being provided with an elongated mouth adapted to encompass said bag frame and being open at the bottom, an endless belt mounted to travel in parallelism with said conveyer, the outer stretch of said belt being connected to said plunger, lugs projecting from the inner stretch of said belt, lugs on the conveyer adapted to engage therewith and lugs on the conveyer adapted to engage said plunger.

4. In a bag turning machine, a conveyer, an endless belt mounted to travel in parallel-

ism with said conveyer, a plunger slidably mounted to travel also in parallelism with said conveyer and having connection with the outer stretch of said belt whereby the plunger is adapted to be moved in a direction opposite to the motion of said conveyer when connection is established between said conveyer and the inner stretch of said belt.

10 5. In a bag turning machine a conveyer, an endless belt mounted to travel in parallelism with said conveyer, a plunger slidably mounted to travel also in parallelism with said conveyer, and having connection with the outer stretch of said belt, lugs on said conveyer adapted to establish connection with the inner stretch of said belt and lugs on said conveyer adapted to establish connection with said plunger whereby the plunger is adapted to travel to and fro when the conveyer is in motion.

6. In a bag turning machine, a conveyer, an endless belt mounted to travel in parallelism with said conveyer and extending beyond the terminal of said conveyer, a plunger slidably mounted to travel also in parallelism with said conveyer, and having connection with the outer stretch of said endless belt, members carried by said conveyer adapted to engage the inner stretch of said endless belt as the conveyer moves and to be released therefrom as they reach the terminal of said conveyer, members mounted on said conveyer adapted to engage said plunger and to be released therefrom as they reach the terminal of said conveyer, whereby a to and fro motion is given to the plunger as the conveyer moves.

7. In a bag turning machine, a conveyer, a bag holder comprising a pair of oppositely disposed wings, means for yieldingly retaining said wings in depressed position on said conveyer, means for raising said wings to a position perpendicular to said conveyer when released from said retaining means, and means for releasing said wings from said retaining means when the said wings pass a predetermined point as the conveyer moves.

50 8. In a bag turning machine, a conveyer, an endless belt mounted to travel in parallelism with said conveyer, a plunger connected to said belt, connections on said conveyer adapted to cooperate with said plunger and cause it to travel alternately in opposite directions through a stroke of predetermined length.

60 9. In a bag turning machine, a conveyer, an endless belt mounted to travel in parallelism with said conveyer, a plunger connected to said belt, connections on said conveyer adapted to engage said belt and thereby cause said plunger to travel in a direction opposite to that of the travel of said con-

veyer, and connections on said conveyer adapted to engage said plunger and cause it to travel in the direction of the motion of said conveyer, both of said connections being adapted to be released when they reach the terminal of the conveyer.

65 10. In a bag turning machine, a conveyer, an endless belt mounted to travel in parallelism with said conveyer, a plunger connected to said belt, connections on said conveyer adapted to engage said belt and thereby cause said plunger to travel in a direction opposite to that of the travel of said conveyer, and connections on said conveyer adapted to engage said plunger and cause it to travel in the direction of the motion of said conveyer, both of said connections being adapted to be released at pre-determined points in the travel of the said conveyer.

70 11. In a bag turning machine, a conveyer, an endless belt mounted to travel in parallelism with said conveyer, a bag holder, a bag frame, a plunger connected to said belt, connections on said conveyer adapted to engage said belt and thereby cause said plunger to travel in a direction opposite to that of the travel of said conveyer, and connections on said conveyer adapted to engage said plunger and cause it to travel in the direction of travel of said conveyer, said connections being adapted to be released at predetermined points in the travel of said conveyer.

75 12. In a bag turning machine, a belt conveyer carrying bag holding means, a plunger mounted to reciprocate in parallelism with said conveyer, a counter weighted pivotally mounted bag frame oppositely disposed with respect to said plunger, and adapted to be encompassed thereby when the plunger and bag frame are in cooperative relation.

80 13. In a bag turning machine, a traveling conveyer, a bag holder, a plunger, and a bag frame, said bag frame projecting from pivotally mounted depending brackets, means for normally maintaining said bag frame in tilted position, a trip adapted to maintain said bag frame in depressed position and to be released at a pre-determined point in the travel of said conveyer.

85 14. In a bag turning machine, a traveling conveyer, a bag frame and a plunger, means carried by said conveyer, for causing the plunger to advance in a direction opposite the direction of travel of said conveyer to accomplish its working stroke, and means carried by said conveyer for causing said plunger to accomplish its return stroke.

90 In testimony whereof, I have signed this specification.

FRANK J. WAGNER.
